SUCKER ROD SWIVEL

Ed Hollyfield, El Dorado, Ark.

Application November 30, 1936, Serial No. 113,399

6 Claims. (Cl. 255—27)

The invention relates to a sucker rod swivel for use in oil well pumps to prevent torsion stresses in, and unscrewing of, sucker rods and at the same time to permit rotational displacement of the pump plunger whereby wear is distributed about the periphery of the plunger.

In the pumping of oil wells a sucker rod transmits reciprocatory motion from the pumping mechanism at the earth's surface to the pump in the lower levels of the well. As pumping continues torsional stresses in the sucker rod may arise because of mechanical conditions in the pump assembly or such stresses may exist at the time of installation of the pump. These stresses may in time lead to unscrewing of the sucker rod which, of course, necessitates removal of the tubing and rod to reconnect the sucker rod sections.

It is an object of the invention to provide a sucker rod swivel to be connected in the sucker rod string to relieve the torsional stresses in the string and hence prevent unscrewing of the sucker rod sections.

It is also an object of the invention to provide in a sucker rod assembly a novel and improved sucker rod swivel to relieve torsional stresses and to permit turning of the reciprocating pump element while in operation, thereby reducing unevenness of wear.

A further object is to provide a swivel that is enclosed, the moving parts thereof being encased in oil whereby friction and resistance to turning are minimized.

A further object is to provide a new and improved construction that effectively swivels the parts connected thereto but which may be made rigid without access thereto if, at any time, such rigid connection is necessary or desirable.

It is also an object of the invention to provide a device of the above indicated characteristics which is simple and substantial in construction, which can be manufactured economically and which is so constructed that a minimum of wear takes place.

Other objects, together with the foregoing, will be apparent from the following description and the drawing which illustrates an embodiment of the invention, it being understood that the description is for purposes of illustration only, and that the invention is to be construed only in view of the prior art and the appended claims. In the drawing:

Fig. 1 is a sectional elevation of the device of the invention.

Fig. 2 is a sectional view of the coupling connection at the upper end of the swivel.

Fig. 3 is a sectional view on line 3—3 of Fig. 1.

Fig. 4 is a sectional view on line 4—4 of Fig. 1.

Referring to Fig. 1, numeral 10 designates the body of the device of the invention. This body is provided with a cylindrical bore 11. A partition 12, which divides the cylindrical body into two parts, is provided with a central opening 13 and presents a downwardly facing shoulder 14. A piston 15 slidably fits within the bore 11 and is provided with a reduced extension 16 which passes through opening 13 and projects beyond the body 10. This extension may be formed integral with the piston 15 or it may, as shown, be made separate and comprise the stem portion 16, a flange portion 17, and a threaded portion 18, whereby the extension and piston may be rigidly interconnected to form a composite unit. An anti-friction bearing 19 is positioned about the extension 16 and is adapted to receive stresses between shoulder 14 and flange 17.

As is best seen in Fig. 3, the lower end of piston 15 is provided with a recess 20 of polygonal cross-section for a purpose that will be made apparent. This recess is shown as being a square cross-section but it is apparent that any desirable cross-section may be provided so long as the intended function is performed.

The body member 10 is provided with threads 21 at its lower end. A plug 22 of special construction is provided with complementary threads and is threadably secured to the body member to form a closure for the bore 11. Extending upwardly from plug 22 and unitary therewith is a projection 23 which terminates below the end of piston 15 thus leaving a small gap 24. As is best seen in Fig. 4, projection 23 is also of polygonal cross-section in order that this projection may fit within recess 20 for a purpose that will be made apparent by the description of the assembly and operation of the device of the invention.

A packing material 25 of any suitable nature is placed about stem 16 above partition 12 and a threaded gland member 26 is screwed into the body member 10 to form a fluid tight seal between the stem 16 and the body 10. A lubricant 30 of suitable viscosity seals all available space in the swivel below the packing 25.

A coupling 9, Fig. 2, is secured to stem 16 through threads 8 and is locked thereto by means of a lock nut 7. The opposite end of coupling 9 is provided with threads 6 to form a box and pin coupling with the sucker rod above the swivel. Plug 22 is provided with threads 27 whereby a

similar connection may be made with the sucker rod below the swivel.

The assembly and operation of the device of the invention is as follows:

- 5 The piston assembly is placed in barrel 10 with the anti-friction bearing 19 in place between shoulder 14 and flange 17. Packing 25 and gland 26 are then placed about stem 16 and the parts thus assembled are held in inverted position.
- 10 Sufficient lubricant is placed in the chamber presented by the open bore 11 to fill all the space that will remain when plug 22 is tightly secured in place. Plug 22 is then screwed in place whereby the swivel is made fluid tight. The swivel is 15 attached in a sucker rod string in an obvious manner.

It is apparent that the enclosed lubricant will provide lubrication that minimizes wear. The lubricant also serves another important function.

- 20 In the normal operation of the device forces acting on the swivel maintain pressure upon the bearing 19. If, however, the unit is placed under a compressive stress there is a slow leakage of the lubricant past piston 15 and the piston will 25 move downward into the body of oil. A succeeding reversal of the stress will again cause the piston to move upward to its original position without impact resulting from the reversal of the stress. This condition is such as may arise in a 30 normal use of the device. Occasions may arise, however, when the rods and/or plunger in the lower levels of the well become sanded up or stuck and it is necessary to remove the pump tubing and sucker rods from the well for repairs.
- 35 In such event it is desirable to turn the sucker rod and hence to back off or unscrew the same at some point in the tubing. This being done, the tubing is then withdrawn from the well until the rods are reached when the same are unscrewed 40 again in like manner until all of the tubing and rods are removed and freed.

In order to lock the swivel against turning to effect unscrewing of the sucker rod below the swivel a downward pressure is applied thereto 45 whereby the lubricant 30 slowly leaks past piston 15 which moves downwardly until projection 23 fits within recess 20. The upper and lower ends of the swivel are then rigidly interconnected making it possible to screw or unscrew the rods without first removing the swivel.

In accordance with the foregoing description it is apparent that the invention provides a sucker rod swivel that functions effectively to prevent unscrewing or the backing off of the sucker rod. 50 The device also distributes wear of the reciprocating parts of the pump, and wear on the tubing, by permitting rotation thereof during pumping operations.

The device of the invention may be used at any 60 desirable point in the sucker rod string. The preferred location has been found to be near the top of the well. For example, seventy-five or one hundred feet from the top. Such assembly is understood to be illustrative only of the use of

the device and applicant does not desire it to be limited thereby.

What is claimed is:

1. A sucker rod swivel comprising a body portion having a downwardly facing shoulder therein, a piston within said body portion and having a cavity in the bottom thereof, a thrust bearing between said shoulder and said piston to receive the thrust between said shoulder and said piston, a plug in the end of said body and means on said plug for engagement with the cavity in said piston for locking the sections against turning movement with relation to each other. 10

2. A sucker rod swivel comprising a body, a partition in said body, an imperforate piston below said partition, a thrust bearing between said piston and said partition, means for closing the body to confine a lubricant therein, and means for connecting said piston and said body respectively to sucker rod sections to attach the swivel 15 in a sucker rod string. 20

3. A sucker rod swivel comprising a cylindrical body member having a bore therein, a partition in said bore, an imperforate piston in said bore below the partition, a stem on said piston extending through an opening in said partition and adapted to be connected to a sucker rod, closure means in the body below said piston, and a lubricant within said body about said piston. 25

4. In a sucker rod swivel, a body, a piston rotatably mounted within said body, means for connecting sucker rod sections to said piston and said body, whereby said rod sections may rotate relative to each other, means for encasing a lubricant within said body about said piston, and means for locking said piston and body against relative turning movement when said piston is moved downwardly through the lubricant in said body. 30

5. A sucker rod swivel including a tubular body, a plug sealing the lower end thereof, a piston in said body, a sucker rod connecting member on said piston extending from the upper end of said housing, means on said body to seal about said member whereby lubricant may be retained 45 in said body, interengaging means between said piston and said plug acting to prevent relative rotation of said piston in said body when said piston is moved relatively downward through the lubricant within the body and means to connect 50 said plug to a sucker rod section. 40

6. A sucker rod swivel including a tubular body, a plug sealing the lower end thereof, an imperforate piston in said body, a sucker rod connecting member on said piston extending from the upper end of said housing, means on said body to seal about said member whereby lubricant may be retained in said body, an antifriction bearing between said sealing means and said piston, interengaging means between said piston and said plug acting to prevent relative rotation of said piston in said body when said piston is moved relatively downward, and means to connect said plug to a sucker rod section. 55 60

ED HOLLYFIELD.
